DEVICE FOR DISPENSING LIQUID IN THE
FORM OF SPRAY

Charles L. Gebauer, Shaker Heights, Ohio, assignor to The Gebauer Chemical Company, Cleveland, Ohio, a corporation of Ohio

Application April 5, 1941, Serial No. 387,055

7 Claims. (Cl. 299—89)

This invention relates to means for dispensing liquids, preferably in the form of a spray, by means of the vapor of a liquid having a low boiling point, with which liquid the materials to be sprayed are admixed or in which the said materials are dissolved. Liquids so admixed or dissolved may be used, for example, in the treatment of diseases or disorders, by inhalation; by application to wounds; and also as lotions and deodorants.

The general object of the invention is to provide a simple, cheap, and efficient device for dispensing in a spray liquids of the character and for the purposes set forth.

I realize the foregoing object in and through the construction and arrangement of parts shown in the drawing hereof, wherein Fig. 1 represents a central vertical sectional view through a device including a receptacle having my novel dispensing and spraying means incorporated therewith; Fig. 2 a similar view, of a modification of the device shown in Fig. 1; Fig. 3 a detail in front elevation of a modification of the means whereby liquid is supplied from a receptacle, such as shown in Figs. 1 and 2, to the delivery opening of the spray nozzle shown in Fig. 1; Fig. 4 a detail in side elevation of the construction shown in Fig. 3; and Fig. 5 a detail in plan of the cap and closure means shown in Fig. 1.

Describing the parts illustrated herein by reference characters, 10 denotes a receptacle provided with a neck 11, the upper end of which is provided with a thread 12 for the reception of the internal thread 13a provided within the neck 13 of a cap adapted to constitute a closure element for the receptacle. The cap is provided with a nozzle structure comprising an external upwardly tapered cap-extension element 14 having an upwardly convergent or frusto-conical bore 15 extending therethrough and a separate nozzle element 16, the lower portion of which is preferably cylindrical and is fitted tightly within a central bore provided therefor in a stopper 17. The upper portion 16a of the nozzle element 16 is of frusto-conical shape whereby it is fitted snugly within the bore 15, with its upper end extending slightly beyond the top of the element 14. The upper end of the nozzle element 16 is provided with a capillary discharge orifice 16c having a diameter of approximately from .004 to .009 inch. In practice, the nozzle element 16 may be made of metal or of any other suitable material; in fact, it may be advantageously made of glass or any other frangible material in which case it can be employed without danger of breakage,

due to the fact that it is mounted within and shielded by the stopper and the nozzle element 14.

The top of the cap is provided with a lateral projection 14a to which a lever 18 is pivoted by means of lugs 18a and a pivot bushing 19. The lever is provided at its upper end with a deformable sealing element 20 which is adapted to engage the delivery end of the nozzle element 16 and is normally held in engagement therewith by means of a spring having a coil 21 intermediate the ends thereof and having arms extending from said coil, one of which arms, 21a, engages the under surface of the lever 18 and the other of which, 21b, has a projection fitted within a notch 14b in the projection 14a.

Referring more particularly to Fig. 1, 23 denotes a tube, the upper end of which extends into the stopper and is fitted about the lower end of the nozzle element 16. 24 denotes a capillary feeding element, such as loosely woven wicking material, located and fitting loosely within the tube 23 and which extends upwardly within the nozzle element 16 without fitting therein so tightly as to defeat its capillary action, the top of said element being in fairly close proximity to the capillary outlet of the nozzle. As shown, the tube 23 preferably extends to the bottom of the receptacle 10 and is provided with prongs 23a, struck therefrom, for the purpose of holding the element 24 in its anchored position as well as for the purpose of supplying liquid and vapor to the said element through the openings 23b, formed in making the said prongs, not only when the level of liquid in the receptacle is normally as high as or extends above one or more of the openings, but when the liquid is brought above one or more of the openings by inverting or tilting the receptacle.

In Fig. 2, I have shown a modification of the construction shown in Fig. 1, wherein the nozzle structure is formed entirely by and within the cap extension element 14x. In this view, the lower portion 15a of the bore of said element is cylindrical, while its upper portion is tapered, as shown at 15b, with a capillary discharge opening 15c at its upper end. A sealing washer 26 is interposed between the top of the neck of the receptacle and the annular shoulder 13x of the cap, said washer having a central opening therethrough registering with the lower end of the nozzle bore for the passage of the capillary feeding element 24 into said bore. The capillary feeding element is shown as enclosed by a tube 27 which may be conveniently formed by rolling a blank of perforated metal of suitable dimen-

sions into tubular form and by providing the upper end of said tube with prongs 27^a adapted to be bent downwardly on top of the washer, thereby to anchor the upper end of the tube in place. One or more prongs 27^b retain the element 24 in its operative position.

In Figs. 3 and 4, there is shown a modification of the tubular element 23 wherein, instead of employing a tube in cooperation with the element 24, I mount said element between substantially flat retaining members 25 and 25^a, said members preferably being formed from an integral piece of metal and extending upwardly from the bottom member 25^b and having their upper ends in substantial engagement with opposite sides of the lower cylindrical portion of the nozzle 16. The capillary element 24 is held in its proper elevated position as well as against lateral shifting by means of the prongs 25^c, 25^d struck respectively from the retaining members 25 and 25^a. Each of these retaining members has been given an ornamental appearance, as shown in Fig. 3. It will be noted that the members 25 and 25^a serve merely to hold the loosely woven capillary wicking in place and have no enclosing function for the latter so that, except for being held against swaying and from dropping out of the nozzle, the said capillary element is, to all intents and purposes, freely accessible from all points below the nozzle to the action of the liquid and vapor in said receptacle.

In all of the embodiments of my invention, free access is provided, above the normal maximum level of the liquid in the receptacle 10, for the vapor from my volatile propellant liquid into the tubes 23 and 27 and between the supporting elements 25, 25^a and into and through the wicking element, thereby insuring the delivery of the liquid from the receptacle in the form of a spray.

In all of the embodiments of my invention, I have found that when using, for example, ethyl chloride as the volatile propellant liquid, which assumes a vaporous condition at ordinary room temperatures, or when the receptacle containing the same is subjected to the heat of the hand of the operator, I am able to deliver, in a spray, materials or substances dissolved in the same propellant liquid or admixed as liquids with the said propellant liquid, or suspended in a very finely divided condition in said propellant liquid.

Having thus described my invention, what I claim is:

1. A dispensing device comprising, in combination, a receptacle for liquid and a closure therefor, said closure including a cap element secured to the top of said receptacle and comprising a nozzle structure including a nozzle passage extending as far as the upper end of the cap element and provided in its upper end with a capillary discharge opening, a capillary feeding element having its upper end mounted within the said nozzle passage and its lower end extending into the lower part of said receptacle thereby to contact liquid therewithin, and movable means normally closing the capillary nozzle opening and adapted to be operated for movement to uncover said opening, the portion of said capillary feeding element which is normally above said liquid being exposed to the free access of vapor under pressure generated from and/or by said liquid and providing for the free passage of vapor therethrough to the said discharge opening.

2. A dispensing device comprising, in combination, a receptacle for liquid and a closure therefor, said closure including a cap element secured to

the top of said receptacle and comprising a nozzle structure including a nozzle passage extending as far as the upper end of the cap element and provided with a capillary discharge opening in the upper end thereof, a capillary feeding element having its upper end mounted within the said nozzle passage and its lower end extending into the lower part of said receptacle, means extending downwardly from said closure and secured to 5 said capillary feeding element for preventing swinging movement thereof and providing for access of liquid thereto and for free access of vapor under pressure thereto above and generated from and/or by said liquid, and movable 10 means normally closing the capillary nozzle opening and adapted to be operated for movement to uncover said opening.

3. In the dispensing device set forth in claim 1, a tube extending downwardly from the said closure and substantially enclosing the capillary feeding element, the said tube being provided with means for engaging the said feeding element thereby to retain the same within the tube and the nozzle passage and with means providing for 20 the free access of liquid to said capillary feeding element and for free access of vapor under pressure thereto above and generated from and/or by said liquid.

4. A dispensing device comprising, in combination, a receptacle for liquid and a closure therefor, said closure including a cap element secured to the top of said receptacle and comprising a nozzle structure including an upwardly convergent passage in the cap element, a nozzle element providing a nozzle passage within said cap element and having an upwardly convergent end portion fitted within the former passage and projecting beyond the top of said closure and provided with a capillary discharge opening in the end thereof, a capillary feeding element having its upper end mounted within the said nozzle element and its lower end extending into the lower part of said receptacle thereby to contact liquid therewithin, and movable means normally closing the capillary discharge opening and adapted to be operated for movement to uncover said opening, the portion of said capillary feeding element which is normally above said liquid being exposed to the free access of vapor under pressure generated from and/or by said liquid and providing for the free 30 passage of vapor therethrough to the said discharge opening.

5. A dispensing device comprising, in combination, a receptacle for liquid and a closure therefor, said closure including a stopper at the upper end of said receptacle and a cap element secured to the top of said receptacle and comprising a nozzle structure including a frusto-conical passage extending upwardly through said cap element, a nozzle element providing a nozzle passage within said cap element and having a frusto-conical upper portion mounted within the frusto-conical passage and extending thereabove and provided with a capillary discharge opening in the upper end thereof, the lower portion of the said nozzle element being mounted within the stopper, a capillary feeding element mounted in said nozzle element and extending into the lower part of said receptacle thereby to contact liquid therewithin, and movable means normally closing the capillary nozzle opening and adapted to be operated for movement to uncover said opening, the portion of said capillary feeding element which is normally above said liquid being exposed to the free access of vapor under pressure 40

generated from and/or by said liquid and providing for the free passage of vapor therethrough to the said discharge opening.

6. In the dispensing device set forth in claim 4, means in proximity to the lower portion of the said nozzle and extending downwardly into the receptacle and engaging the capillary feeding element thereby to prevent swinging movements of the latter, the last mentioned means being provided with means providing for the free access of liquid to said capillary feeding element and for the free access of liquid to said capillary feeding element and for the free access of vapor under pressure thereto above and generated from and/or by said liquid.

7. In the dispensing device recited in claim 4, a tube having its upper end surrounding the lower end of the nozzle within the stopper and substantially enclosing the capillary feeding element, the said tube being provided with openings providing for the free access of liquid to said capillary feeding element and for the free access of vapor under pressure above and generated from and/or by said liquid and with one or more projections extending inwardly therefrom for engaging said feeding element thereby to retain the same within the tube and the nozzle element.

CHARLES L. GEBAUER.
